To all whom it may concern:
Be it known that I, Thomas P. Hayes, a citizen of Canada, residing at Cambridge, in the county of Middlesex and Commonwealth of Massachusetts, have invented a new, original, and ornamental Design for Composition Floor Covering, of which the following is a specification, reference being had to the accompanying drawing, forming a part thereof, in which:

Fig. 1 is a plan view of a composition floor covering, showing my new design.

Fig. 2 is an enlarged fragmentary perspective view thereof.

The repeat unit is enclosed within the dot-and-dash lines.
